(57) **CLAIM**

The ornamental design for a combined inbuilt computer keyboard and lap desk, as shown and described.

DESCRIPTION

FIG. 1 is a top perspective view of a combined inbuilt computer keyboard and lap desk;

FIG. 2 is a bottom perspective view of the combined inbuilt computer keyboard and lap desk of FIG. 1;

FIG. 3 is a top plan view of the combined inbuilt computer keyboard and lap desk of FIG. 1;

FIG. 4 is a bottom plan view of the combined inbuilt computer keyboard and lap desk of FIG. 1;

FIG. 5 is a front elevational view thereof;

FIG. 6 is a rear elevational view thereof;

FIG. 7 is a right side elevational view thereof; and,

FIG. 8 is a left side elevational view thereof.

The ornamental design which is claimed is shown in solid lines in the drawings. Any broken lines in the drawings are for illustrative purposes only and form no part of the claimed design.
